THOMAS ALLSOP AND WALTER W. SIBSON, OF PHILADELPHIA, PENNSYLVANIA, ASSIGNORS TO THE PHILADELPHIA DRYING MACHINERY COMPANY, OF PHILADELPHIA, PENNSYLVANIA, A CORPORATION OF PENNSYLVANIA.

SINGEING-MACHINE.

No. 895,711.

Specification of Letters Patent.

Patented Aug. 11, 1908.

Application filed February 17, 1908. Serial No. 416,295.

To all whom it may concern:

Be it known that we, THOMAS ALLSOP and WALTER W. SIBSON, citizens of the United States, residing at Philadelphia, in the county of Philadelphia and State of Pennsylvania, have invented certain new and useful Improvements in Singeing-Machines; and we do hereby declare the following to be a full, clear, and exact description of the invention such as will enable others skilled in the art to which it appertains to make and use the same.

This invention relates to improvements in singeing machines primarily designed for use in finishing stockings, and is more specifically related to the type of singeing machine previously invented by us, and made the subject-matter of a companion application for patent.

In the application referred to is disclosed a singeing machine in which is embodied means for singeing the stockings, means for removing the carbonized fiber from the singed stockings, and a carrier provided with forms for the stockings, which carrier is mounted to have a fixed path of movement in relation to the singeing and fiber-removing means. During such movement the stockings are subjected to the different steps incident to singeing, and after completing the cycle of operations the forms are returned successively to the point of application of the stockings thereto, at which point the forms are charged with unsinged stock. This machine, however, is a horizontal one, that is to say, the carrier for the stockings is arranged to operate in a horizontal plane, and the other elements of the machine are correspondingly arranged in order to fully coöperate with the carrier. By reason of such arrangement the machine in question requires considerable floor space, comparatively speaking, and its use in factories and mills where economy of space is desirable, is attended with some objections. The present invention, therefore, has as its primary object the production of a singeing machine which, while preserving the salient and desirable features of the previous type of machine, will overcome the objections noted and provide a construction that can be used with great economy of floor-space, the carrier for the stockings being mounted to operate in a vertical plane, and one wherein the parts are

thoroughly compacted together, thus imparting to the machine great strength, and enabling the machine to operate with a minimum expenditure of power.

Having this general object in view, and other minor ones that will appear as the character of the invention is better understood, the invention consists substantially in the novel construction, combination and arrangement of parts hereinafter fully described, illustrated in the accompanying drawings, and pointed out in the appended claims.

In the drawings, Figure 1 is a side elevation of a singeing machine constructed in accordance with and embodying the principles of the present invention. Fig. 2 is a top plan view thereof. Fig. 3 is an end elevation of the machine. Fig. 4 is a transverse sectional view of the machine frame on the line 4-4, Fig. 1, the burner tubes being shown in elevation. Fig. 5 is an elevation illustrating another form of carrier for the stockings.

Referring in detail to the drawings, the numeral 1 designates the frame of the herein-described machine, said frame comprising elongated side members 2 each of which is provided with a supporting leg 3, and connected to said side members 2, at the end thereof opposite to the legs 3, is a supporting standard 4.

Arranged upon each of the side members 2, at a point approximately midway its ends, is a journal-block 5, and mounted within said blocks 5 is a transversely-extending shaft 6 upon which is arranged a head 7. This head, as in the construction of carrier disclosed in our former machine, may be sectional, and projecting radially from the head 7 is a plurality of skeleton forms 8, which forms may be made of stout wire. The head 7 and the forms 8 constitute the carrier for the stockings, and it will be observed that this carrier is free to rotate between the side members 2 of the frame for successively presenting the stockings to the singeing and fiber-removing means, and the means for removing the singed stockings from the forms, as will fully appear hereinafter.

The singeing means just referred to comprise a pair of inclined burner tubes 9, the inner side of each of said tubes being perforated for the escape of the combustible mix-

ture that forms the singeing flames. These tubes 9 extend in a radial direction relatively to the head 7, each being supported by an elbow 10 in such inclined position, a pipe 11 being connected to each of said elbows, which pipe has its lower end fitted in a supporting bracket 12 arranged upon the upper side of one of the side members 2. It will thus be seen that the supporting brackets 12 firmly hold the burner tubes 9 in proper relation to the stocking carrier, and each of said tubes is also provided with a mixing device 13 for causing the admixture of air and gas that is introduced to the tubes 9 to provide the singeing flames.

Mounted in proximity to the burner tubes 9 are the means for feeding the unsinged stockings to the forms 8. These means comprise a pair of endless brush-conveyers 14, one of said conveyers being carried by each of the side members 2 at a point substantially above the leg 3 thereof, and each of said conveyers 14 is mounted upon a pair of rollers 15 carried by shafts 16, said shafts being journaled in suitable bearings 17 that are also carried by the inner face of the side members 2. Each of the rolls 15 is provided, adjacent its lower end, with a supporting flange 18, and thus the conveyers are prevented from working downwardly on the rollers 15. It will, of course, be understood that the bristles of said brush-conveyers, at the contiguous stretches of the latter, extend inwardly sufficiently to cover and act upon each of the forms 8 as the same are positioned between said brush conveyers, and inasmuch as the contiguous stretches of the brush-conveyers 14 move in the same direction, or towards the head 7, it will be seen that when the open mouth of a stocking is presented to the bight of said conveyers the stocking is carried by the latter along the forms, being effectually stretched thereon during such movement, and thus being freed of wrinkles. These conveyers 14 are substantially the same length as an ordinary stocking, so that under the action of the conveyers the full length of the stocking is applied to each of the forms 8. It will be noted that the inner shaft 16 of each of the conveyers 14 has its lower end elongated and seated in a suitable bearing 19 carried by each of the side members 2, which bracket is also provided with a horizontally-disposed bearing sleeve 20, and said sleeves 20 receive a pair of horizontally-disposed shafts 21 that extend longitudinally of the machine frame, each of said shafts having a miter gear 22 thereon that meshes with a similar gear 23 carried at the lower end of each of the inner shafts 16. It is thus evident that the shafts 21 will effectually drive the brush conveyers 14.

At a point between the head 7 and the supporting standard 4, and spaced above the top of the machine frame, is arranged a pair

of rotary brushes 24. These brushes are parallel with the tops of the side members 2, and serve the purpose of removing the carbonized fiber from the singed stockings. The brushes 24 are mounted upon shafts 25 the inner ends 70 of which are journaled in supporting standards 26, while their outer ends are journaled in the upper end of the supporting standard 4, and mounted upon each of the shafts 25, at the outer side of the standard 4, is a gear 75 27, said gears meshing with each other, and thereby serving to maintain simultaneous rotation of the brushes 24. For effecting this movement of the brushes, one of the shafts 25 has a driving pulley 28 connected thereto, said pulley deriving its power from a source to be presently described. By arranging the brushes 24 in the manner described, it will be seen that each of the forms 8 is successively presented to and passed between said brushes, and the bristles of the latter effectually serve to remove from the singed stockings the carbonized fiber resulting from the action of the singeing flames.

For the purpose of removing the singed 90 stockings from the forms 7 a pair of vertically-arranged rotary brushes 29 is employed. One of these brushes is carried by each of the side members 2, the brushes being mounted upon vertically-extending shafts 30 that are 95 carried by upper bearings 31 and lower bearing 32 that are alined with the bearings 31, each of the bearings 32 being also provided with a horizontally-disposed sleeve 33, which sleeves receive the shafts 21. The brushes 100 29 are caused to rotate in unison through the medium of intermeshing gears 34, one of said gears being carried by each of the shafts 30, and for driving these gears it will be noted that one of the shafts 30 has its lower end 105 elongated and provided with a horizontally-disposed driving pulley 35. Each of the shafts 30 is also provided with a miter gear 36, said gears meshing with similar gears 37 that are carried by the shafts 21, and by 110 reason of this construction the shafts 21 receive their power from the driving pulley 35, and in turn operate the brush-conveyers 14.

It will be observed that the brushes 29 are below the fiber-removing brushes 24, and that they rotate in a plane at right angles to the plane of rotation of the brushes 24. Therefore, as each stocking, carried by its form, leaves the brushes 24, it is introduced to the bight of the brushes 29, which brushes immediately seize upon the toe-portion of the stocking, and remove the same from the form upon which it was previously supported. To permit such removal the upper portion of the supporting standard 4 is provided with a 125 discharge opening 38, and under the action of the brushes 29 the singed stockings are ejected through said opening 38, at which point they may be received by a suitable receptacle, or, if desired, deposited upon any 130

suitable form of conveyer to be taken by the latter from the machine.

It is, of course, necessary, as in the former type of machine, to impart an intermittent movement to the stocking carrier. To this end the shaft 6 is provided with a mutilated gear 39, which gear is in the form of a miter gear, and coacting with said gear 39 is a second mutilated miter gear 40 that is carried by a longitudinally-extending shaft 41 journaled in suitable brackets 42. The teeth of the gear 40 cover only a segment of said gear, and the gears 39 and 40 are so proportioned that the former makes only one-quarter of a revolution to each revolution of the latter. With the gears 39 and 40 so related that one of the forms 8 is normally between the brush conveyers 14, it will be noted that at each revolution of the gear 40 the stocking carrier is rotated 90 degrees, and in such movement carries the unsinged stocking from the conveyers 14 through the burner tubes 9, at which point the singeing action takes place, and after leaving said burner tubes the conveyer comes to rest. This constitutes its first dwell, and when the carrier is moved again the stocking passes between the fiber-removing brushes 24, at which point the carbonized fibers are brushed from the stocking, and at the next dwell the stocking is positioned immediately opposite the bight of the brushes 29. As before stated, these immediately seize upon the toe-portion of the stocking and draw the latter from the form, discharging the singed stocking through the opening 38, and after the form has been thus relieved of the stocking the same is advanced to the brush conveyers 14, to be again charged with unsinged stock, and to repeat the cycle of operations that has just been described.

For driving the various parts of the machine a counter-shaft 42 is employed, upon which shaft the usual tight and loose pulleys are found. A pulley 43 is mounted upon the shaft 42, over which pulley passes a belt 44, and this belt also passes over a pulley 45 that is carried by the shaft 41, so that this shaft is actuated directly from the counter-shaft 42; a pulley 46, also carried by the shaft 42, has a belt 47 passing thereover, which belt connects said pulley with the pulley 28, and the carbonized fiber-removing brushes 24 are also likewise driven direct from the shaft 42, and in order that the brushes 29 may be so driven, a pulley 48, carried by the shaft 42, is connected to the pulley 35 through the medium of a belt 49, said belt passing over a pair of idler pulleys 50 sustained by a supporting bracket 51 carried by the supporting standard 4. Thus it will be seen that the shaft 42 serves to drive all the parts of the machine, the brush-conveyers 14, the fiber-removing brushes 24, and the stocking-moving brushes 29 operating continuously,

while the stocking carrier is driven intermittently from the continuously-operating shaft 41.

By reason of the fact that the carrier head 7 is necessarily limited in the number of forms 8 supported thereby, and as it may be desirable to increase the capacity of the machine, recourse is had to the construction disclosed in Fig. 5 of the drawings under such conditions. By referring to that figure it will be observed that the forms 8 are carried by an endless conveyer 52, which conveyer may be a sprocket chain or made up of links, and the conveyer 52 is sustained by a pair of rotating heads 53, one of which corresponds to the head 7, and is likewise mounted upon a shaft similar to the shaft 6 to be intermittently driven by the gears 39 and 40. In driving the conveyer 52, the gears may be so proportioned as to cause only one of the forms to pass through the respective treating devices of the machine, or to cause a series of the same to pass therethrough at each periodical movement of the driving mechanism. By this construction a plurality of operatives may be employed for applying the unsinged stockings to the forms, or a series of the brush conveyers 14 may also be employed for this purpose if it is desired to accomplish the feeding of the unsinged stock automatically.

Having thus described the invention, what is claimed as new, and desired to be secured by Letters Patent, is:

1. In a machine of the class described, a carrier for the articles to be singed mounted to operate in a vertical plane, singeing means associated with said carrier, and means for imparting to said carrier successive dwells to progressively advance the articles to be singed in relation to the singeing means.

2. In a machine of the class described, a carrier for the articles to be singed mounted to operate in a vertical plane, singeing means associated therewith, and means also associated with said carrier for removing the carbonized fiber from the singed articles.

3. In a machine of the class described, a carrier for the articles to be singed mounted to operate in a vertical plane, singeing means associated with said carrier, means also associated with said carrier for removing the carbonized fiber from the singed articles, and means for removing the singed articles from said carrier.

4. In a machine of the class described, a carrier for the articles to be singed, said carrier being mounted to operate in a vertical plane and having a fixed path of movement, singeing means associated with said carrier, and means for imparting to said carrier successive dwells to progressively advance the articles to be singed in relation to the singeing means.

5. In a machine of the class described, a

- carrier for the articles to be singed, said carrier being mounted to operate in a vertical plane and having a fixed path of movement, singeing means associated with said carrier, 5 and means for removing the carbonized fiber from the singed articles.
6. In a machine of the class described, a carrier for the articles to be singed, said carrier being mounted to operate in a vertical plane and having a fixed path of movement, singeing means associated with said carrier, 10 means for removing the carbonized fiber from the singed articles, and means for removing the singed articles from said carrier.
- 15 7. In a machine of the class described, a carrier for the articles to be singed mounted to operate in a vertical plane, means for feeding the articles to be singed to said carrier, and singeing means associated with said carrier.
- 20 8. In a machine of the class described, a carrier for the articles to be singed mounted to operate in a vertical plane, means for feeding the articles to be singed to said carrier, singeing 25 means associated with said carrier, and means for removing the carbonized fiber from the singed articles.
- 30 9. In a machine of the class described, a carrier for the articles to be singed mounted to operate in a vertical plane, means for feeding the articles to be singed to said carrier, singeing means associated with said carrier, 35 means for removing the carbonized fiber from said carrier, and means for removing the singed articles from the carrier.
- 40 10. In a machine of the class described, a carrier for the articles to be singed, said carrier being mounted to operate in a vertical plane and having a fixed path of movement, singeing means, and carbonized fiber-removing 45 means, said singeing means and carbonized fiber-removing means being arranged about said carrier and in its path of movement.
- 50 11. In a machine of the class described, a carrier for the articles to be singed, said carrier being mounted to operate in a vertical plane and having a fixed path of movement, singeing means, and carbonized fiber-removing means, said singeing means and carbonized fiber-removing means being arranged about said carrier and in its path of movement, and means arranged in proximity to the carbonized fiber-removing means for re- 55 moving the singed articles after the latter have left said carbonized fiber-removing means.
- 60 12. In a machine of the class described, a frame, a carrier journaled in said frame and operating in a vertical plane, said carrier supporting the articles to be singed, and singeing means also carried by said frame.
- 65 13. In a machine of the class described, a frame, a carrier journaled in said frame and operating in a vertical plane, said carrier supporting the articles to be singed, singeing means also carried by said frame, and means carried by said frame and acting upon the singed articles after the latter have left the singeing means to remove the carbonized fiber therefrom. 70
14. In a machine of the class described, a frame, a carrier journaled in said frame and operating in a vertical plane, said carrier supporting the articles to be singed, singeing means also carried by said frame, means carried by said frame and acting upon the singed articles after the latter have left the singeing means to remove the carbonized fiber therefrom, and means for removing the singed articles after the latter have left the carbonized fiber-removing means. 75
15. In a machine of the class described, a frame, a carrier journaled in said frame and operating in a vertical plane, said carrier supporting the articles to be singed, means for feeding the articles to be singed to said carrier, and singeing means also carried by said frame. 80
16. In a machine of the class described, a frame, a carrier journaled in said frame and operating in a vertical plane, said carrier supporting the articles to be singed, burner devices carried by said frame and between which the articles to be singed are passed by said carrier, and means for removing the carbonized fiber from said articles. 85
17. In a machine of the class described, a frame, a carrier journaled in said frame and operating in a vertical plane, said carrier supporting the articles to be singed, burner devices carried by said frame and between which the articles to be singed are passed by said carrier, and brushes for removing the carbonized fiber from said articles. 90
18. In a machine of the class described, a frame, a carrier journaled in said frame and operating in a vertical plane, said carrier supporting the articles to be singed, burner devices carried by said frame and between which the articles to be singed are passed by said carrier, brushes for removing the carbonized fiber from the singed articles, and brushes for removing the singed articles from said carrier after the same have left the carbonized fiber-removing brushes. 100
19. In a machine of the class described, a frame, a carrier journaled in said frame and operating in a vertical plane, said carrier supporting the articles to be singed, burner devices carried by said frame and between which the articles to be singed are passed by said carrier, horizontally-arranged brushes journaled upon said frame for removing the carbonized fiber from said articles, and means for removing the singed articles from said carrier after the same have left the fiber-removing brushes. 105
20. In a machine of the class described, a frame, a carrier journaled in said frame and 110
- 120
- 125
- 130

operating in a vertical plane, said carrier supporting the articles to be singed, burner devices carried by said frame and between which the articles to be singed are passed by said carrier, horizontally-arranged brushes journaled upon said frame for removing the carbonized fiber from said articles, and vertically-arranged brushes also carried by the frame for removing the singed articles from

said carrier after the same have left the fiber-removing brushes.

In testimony whereof we affix our signatures, in the presence of two witnesses.
